Inventor
HANS BROCKMÜLLER
By his Attorney
Hauswirth & Linsen

UNITED STATES PATENT OFFICE.

HANS BROCKMÜLLER, OF NEW YORK, N. Y.

PHONOGRAPH.

1,281,282.

Specification of Letters Patent. Patented Oct. 15, 1913.

Application filed January 28, 1913. Serial No. 212,326.

To all whom it may concern:

Be it known that I, HANS BROCKMÜLLER, a citizen of Germany, and a resident of New York city, in the county and State of New York, have invented certain new and useful 5 Improvements in Phonographs, of which the following is a specification.

This invention relates to a novel phonograph which is so constructed, that its operative parts may be separately mounted upon 10 and removed from an ordinary table or similar support, thus dispensing with the use of the cabinet heretofore generally employed. In this way, the cost of the cabinet is saved, 15 and the additional piece of furniture which it represents, is entirely done away with, so that the device is available to persons of limited means or possessing but restricted dwelling accommodations. The invention 20 consists in the various features of novelty more fully pointed out in the specification and appended claims.

In the accompanying drawing:

Figure 1 is a plan of a phonograph embodying my invention;

Fig. 2, a side view partly in section, and Fig. 3, a section on line 3—3 Fig. 2.

The turn table 1 of the phonograph is provided with a depending tapering spindle 2, adapted to be projected through an aperture of a table or other support 3. To the lower side of table 3, there is affixed a suitable motor 4 the shaft 5 of which carries a worm 6, that engages a worm wheel 7, fast 35 on an upright shaft 8, located beneath support 3 and turning in bearings 9, that are secured to motor 4. Shaft 8, is furnished with an upper coned socket 10, that is adapted to receive and support the protruding 40 tapered end of spindle 2, so that by passing said spindle through table 3, into engagement with socket 10, the turn table will become at once frictionally coupled to the motor, while it may be as readily uncoupled 45 by being raised off the table. With the embodiment shown, shaft 8, is likewise furnished with a lower coned socket, which permits the shaft to be reversed when worn, or the motor to be mounted on top of table 50 3, in lieu of being secured to the lower side thereof, but this lower socket may manifestly be dispensed with if desired.

Upon table 3, is further adapted to be placed, a base 11, for the tone arm 12, said base being removable from the table; and

entirely disconnected from turn table 1, or its operative mechanism. Base 11, is of conical form, and projects into the downwardly directed rear belled end 13 of the Elbowed tone arm 12, which is raised a distance off the lower end of the base, so as to form an intervening clearance for the sound waves above the table. In this way, the tone arm is made to assume the additional function of the conventional horn, which with my construction, is entirely done away with.

In order to obtain the necessary universal movement of the tone arm, it is shown to be connected to base 11, by means of an axially rotatable pin 14, which extends upwardly from the latter and is fulcrumed at its upper eyed end to a bridge 15, extending across the tone arm.

When the phonograph is to be played, it is merely necessary to mount the turn table 75 upon table top 3, in manner previously described, place the base of the tone arm upon said table top, in proximity to the turn table, and start the motor. When the playing is finished, the turn table, and tone arm are 80 lifted off the table top, and may then be separately or collectively stored away in a drawer or similar container.

It will be seen that by my invention, the table top requires no mutilation whatsoever, 85 excepting the small aperture for the spindle, which is unobtrusive and may be readily covered up, the motor when attached to the lower face of the table top, being invisible. Inasmuch as the turn table and the tone 90 arm, are separable from the table top, from the motor, and from each other, they may be packed and stored within a minimum space, which space is further reduced by the entire absence of a cumbersome horn. In 95 this way, the device may be readily transformed from operative engagement, into inoperative assemblage, so that while fully performing its function in the former condition, it is entirely unobtrusive in the latter condition.

I claim:

1. The combination of a conventional support such as a table, said support having an aperture, with a turn table removably 105 mounted on said support, a tapered spindle that projects from the turn table downwardly through said aperture, a motor affixed to the lower side of the support, and a socketed shaft operable by the motor and 110

located likewise beneath said support, said shaft being adapted to frictionally engage the tapered spindle.

2. A phonograph comprising a conventional support such as a table, a coned base removably supported thereby, an elbowed tone arm having a downwardly directed belled end into which said coned base projects, and means for pivotally connecting 10 the tone arm to said base.

3. A phonograph comprising a conventional support such as a table, said support having an aperture, a turn table removably mounted on the support, a spindle that projects from said turn table downwardly through said aperture and is adapted to be removably coupled beneath said support to 15 a motor, a base also removably mounted on

said support, an elbowed tone arm having a downwardly directed belled end, and means 20 for pivotally connecting the tone arm to said base.

4. A phonograph comprising a conventional support such as a table, said support having an aperture, a turn table removably 25 mounted on the support, a spindle that projects from said turn table downwardly through said aperture, and is adapted to be removably coupled beneath said support to a motor, a coned base also removably mounted 30 on the support, an elbowed tone arm having a downwardly directed belled end that projects over the coned base, and means for pivotally connecting said tone arm to said base.

HANS BROCKMÜLLER.
